WRENCH-TYPE COMBINATION TOOL
Edward Clifford Green, 159 Highway 36,
Belford, N.J. 07718
Filed Oct. 29, 1964, Ser. No. 407,406
1 Claim. (Cl. 7—7)

The present invention relates, in general, to a wrench-type combination tool and, in particular, to a combination tool which may be employed conveniently to perform essentially all related functions necessary to the operation of propane-type torches and tanks.

In the utilization of presently available propane-type torches and tanks, e.g., "Prest-O-Lite" torches and tanks, it has heretofore been necessary to provide a number of different tools for effecting the various operations ancillary to such utilization. For example, a number of conventional tools have been provided to connect and disconnect hose fittings on Prest-O-Lite tanks as well as the burner tip employed with the propane tanks used in conjunction therewith. Further, a key has been provided for and opening closing the valves on the Prest-O-Lite tanks as well as a separate key for opening and closing the valves on the propane tanks, so-utilized. In addition, a flint sparker has been provided to ignite the Prest-O-Lite torch. During such operation it has also been found necessary to readily provide extra flints for the sparker and, after prolonged use, a cleaner for the burner tip of the torch.

The foregoing operations performed in conjunction with the torch and tanks have, therefore, necessarily involved the use of a number of separate and distinct tools. Thus, an operator utilizing the torch and tanks mentioned above would be required to carry each of a relatively large number of tools so as to effect each of the desired operations. It is manifest, therefore, that it would be highly advantageous to provide a single tool which can capably perform all of the above plurality of different operations. It is also manifest that a tool which utilizes the same components in mutual combination for a number of different successive operations is even further advantageous.

Accordingly, it is an object of the present invention, therefore, to provide a combination tool which provides the same components in mutual operative combination so as to successfully effect a number of different operations.

It is also an object of this invention to provide a single combination tool which will capably perform essentially all of the operations necessary in conjunction with propane-type torches and tanks.

It is a still further object of this invention to provide a combination tool which is comprised of a plurality of elements which act in mutual combination so as to accomplish essentially all of the operations performed in conjunction with Prest-O-Lite-type torches and tanks.

These and other objects of the invention are attained and will become immediately apparent by the construction and operation of such combination tool as herein-after more fully described, reference being made to the accompanying drawings forming a part hereof, wherein like numerals refer to like parts throughout and in which:

FIGURE 1 is a front elevation of a preferred embodiment of the wrench-type combination tool of this invention;

FIGURE 2 is a side view of the wrench-type combination tool of this invention with the striker lever thereof being in detached position;

FIGURE 3 is an exploded view of the wrench-type tool in accordance with this invention.

Referring now specifically to FIGURES 1-3, the com-

2

bination tool of this invention is shown comprising a frame 10, generally in the shape of the letter T and thus comprises at least two horizontal arm members 12 and 14, respectively, and a vertical member 16. The vertical member 16 of frame 10 is provided with a rack gear 18 which extends from about midway of said vertical member up to that portion of the frame where the vertical member joins the horizontal members 10 and 12, respectively.

5 A jaw member 20 is provided having an opening 22 extending therethrough. Said opening 22 is of such configuration so as to accommodate at least a portion of the vertical member 16 of the frame therein and thus allow sliding movement of the jaw member 20 along the axis of the vertical member 16. The jaw member 20 is adjustably movable with closing and opening movement controlled by a worm thumb wheel which engages the teeth provided in a rack gear 18. The worm thumb wheel 24 is held in place within the jaw member 20 by 10 means of elongated machine screw 26 which extends through the coaxially arranged cylindrical recesses 28 and 30 provided for in jaw member 20 and worm thumb wheel 24. The face 32 of jaw member 20, as well as the bottom portion 34 of horizontal arm member 12 which formed the jaws of the wrench of the instant invention, are preferably provided with uneven or knurled surfaces so as to insure sufficient "bite" when such members are employed for wrench-type operations.

15 Integrally connected with frame 10 and positioned at the terminal end of vertical member 16 is positioned a socket wrench 36 comprising a cylindrical peripheral portion 38 and a centrally disposed square recess 40 disposed therein. In operation, the square recess 40, which is adapted to receive a square stem, engages said stem 20 which is provided on the valve of propane tanks. By turning right or left on the horizontal arm members 12, 14, of the wrench frame 10, the valve on said propane tanks will be either opened or closed according to the 25 direction of motion. Thus, it is apparent that the jaws of the wrench portion of the instant invention, along with the remaining horizontal member, mutually comprise arms affording leverage for the socket wrench provided on the frame thereof.

30 Striker lever 42 which is positioned on vertical member 16 of the frame and comprises an elongated member which is bifurcated at one terminal end 44 thereof. The vertical member 16 is operably connected with a recess 46 of the bifurcated portion 44 of the striker lever. The striker lever 42 is pivotably mounted on the frame 10 by means of a machine screw or similar fastening means which passes through coaxially aligned cylindrical taps 48 provided in both the bifurcated portion of the striker lever 42 and the frame 10, respectively. The other end 40 of the striker lever 42, is provided with a flint 52 which is affixed to the striker lever by conventional means, i.e., 35 machine screw and the like.

40 On the planar or face portion of frame 10, comprised of horizontal members 12 and 14, is affixed a striker plate 54 which is comprised of a material which will provide a spark upon contact of flint 52 on said striker plate. Striker plate 54 is affixed to said frame by means of a plurality of machine screws 56 or the like which pass through striker plate 54 and striker backup plate 58 on which said striker plate is positioned.

45 Flint 52, affixed to the striker lever 42, is normally positioned at the extreme end portion of striker plate 54 by means of spring 60 which, when in its normally extended position, forces striker lever 42 to an extreme rotatable position about the axis comprised of machine screw 46.

50 In operation, upon movement of the striker lever, e.g., from left to right, and conjoint movement of the flint

across the striker plate, the flint creates sparks by friction with said striker plate. Advantageously, these sparks are capable of igniting Prest-O-Lite torches and similar gas burning equipment. Upon creation of the desired sparks, spring 60 presses against the striker lever 42 forcing same back to its original extended starting position.

In accordance with the present invention, there is provided one or more square apertures 64 which pass through the vertical member 16 of frame 10. By placing any one of such apertures over the square stem provided on the valve of Prest-O-Lite tanks, and turning the combination tool of this invention rotatably to the right or left, the valve will open or close, depending on the direction of motion provided.

In accordance with this invention, there is also provided in the terminal ends 66 and 68 of the horizontal members of the frame, two recesses 70 and 72, respectively. Each of said recesses 70 and 72 are annularly threaded at the outermost terminal portion thereof and are provided with screw plugs 74 and 76 which, when threadably positioned within the terminal portions 66 and 68, respectively, of the horizontal members, thereby form a storage area within each of said horizontal members. Accordingly, in that storage area formed by recess 70 and screw plug 74 may be advantageously stored extra flints for operation with the striker portion of the tool of this invention. Screw plug 76 may advantageously have a fine needle-like member attached thereto, and stored within recess 72 and which may be used, upon removal, for cleaning the extremely small gas orifices of propane and similar tanks.

Thus, a device for the complete operation of propane-type torches and tanks is provided in a single tool which also provides various storage spaces for often needed parts, etc. In order to accomplish this, it will be observed that one of the horizontal members of the frame of the tool used for leverage in rotating the socket wrench portion of the tool also comprises a jaw of the adjustable wrench portion of said tool. Similarly, the vertical member of the frame mutually comprises not only said adjustable wrench's handle and the axis of said socket wrench, but also provides a suitable member on which the striker arm and on which the striker plate may be affixed. Con-

jointly, such vertical member also provides that suitable member in which one or more useful keys comprising a square recess is provided. Accordingly, the horizontal members which also comprise the jaws of said wrench as well as the handle of said socket wrench, as set forth above, also provides the valuable storage space for parts integral in the operation of torches and tanks.

The foregoing is considered as illustrative of the principles of the invention. Further, since numerous modifications and changes will readily occur to those skilled in the art, it is not desired to limit the invention to the exact construction and operation shown and described and, accordingly, all suitable modifications and equivalents can be resorted to, falling within the scope of the invention as claimed.

What is claimed is:

A combination tool comprising a T shaped frame having a vertical member and two horizontal members integral therewith and extending therefrom; said vertical member having slidably positioned thereon a jaw member which with one of said horizontal members forms the jaws of an adjustable wrench, a striker plate affixed to said horizontal members; said vertical member having pivotably mounted thereon an elongated striker lever with a flint affixed thereto, said flint being in abutting contact with said striker plate and providing sparks when moved across said striker plate, said slideable jaw being positioned between said striker plate and said striker lever pivot, and said vertical member having a socket positioned on the terminal end thereof.
